FIG. 1

FIG. 2

FIG. 3

FIG. 4

FIG. 5

1
BABY CARRIER

TECHNICAL FIELD

Baby Carriers

BACKGROUND

There are many various infant and baby carriers available on the market for parents and other caregivers to carry babies and infants while keeping the caregiver's hands free. Many of these are constructed with support straps going over the wearer's shoulders, putting strain on the user's shoulders.

SUMMARY

A baby carrier has a baby pouch, a pair of shoulder straps extending from opposite sides of an upper portion of the pouch, a waistband extending from opposite sides of a lower portion of the pouch and side straps extending from respective sides of the pouch intermediate the shoulder straps and waistband, the side straps being configured to couple together.

In various embodiments, there may be included any one or more of the following features: the shoulder straps are configured to be secured to each other by tying; an adjustable height headrest; the baby pouch forms an adjustable seat for a child; the baby pouch comprises a drawstring; the waistband comprises an adjustable buckle; the side straps are configured to couple together by an adjustable buckle.

These and other aspects of the device and method are set out in the claims.

BRIEF DESCRIPTION OF THE FIGURES

Embodiments will now be described with reference to the figures, in which like reference characters denote like elements, by way of example, and in which:

FIG. 1 shows an outer side of a baby carrier laid flat with the headrest folded.

FIG. 2 shows the baby carrier of FIG. 1 with the headrest unfolded.

FIG. 3 is a perspective view of a baby carrier in a back-carry position.

FIG. 4 shows a baby carrier in an example carry configuration with the side straps placed under the shoulder straps.

FIG. 5 shows a baby carrier in an example carry configuration with the side straps placed over the shoulder straps.

DETAILED DESCRIPTION

Immaterial modifications may be made to the embodiments described here without departing from what is covered by the claims.

A baby carrier 10 is wearable to secure a baby or infant to a user. The baby carrier provides an efficient way of carrying a child by keeping the weight of the child close to the body of the user. The baby carrier may be used to carry a baby or infant in a front carry, side carry or back carry position.

The baby carrier comprises a baby pouch 12, waistband 14, side straps 16A and 16B and shoulder straps 18A and 18B as shown in FIGS. 1 and 2. The waistband 14 extends from opposite sides of a lower portion of the baby pouch 12, the shoulder straps 18A and 18B extend from opposite sides of an upper portion of the baby pouch 12, and the side straps

2

16A and 16B extend from respective sides of the baby pouch 12 intermediate the shoulder straps 18A and 18B and the waistband 14. The shoulder straps, side straps and waistband are secured to the baby pouch 12 and may be sewn to the baby pouch 12.

Multiple straps may be used to decrease the strain on the user's shoulders, allowing the user to comfortably carry the child for long periods of time. The baby is held between the body of the user and the baby pouch 12. Side straps offload weight from the shoulder straps and redistribute it around the user's torso and hips such that there is minimal to no weight bearing through the shoulders.

The side straps help to make the carrier a safe option for use with children with low trunk tone and babies who cannot yet sit upright unaided. The side straps allow the baby pouch to be positioned such that the child's trunk and pelvis are held in a neutral position. The opening created between the side straps and the waistband on either side of the pouch is preferably large enough for the child's legs to comfortably fit through, but too small for the child to slip out of the pouch. The side straps may also help to reduce lateral sway of the child on the user's back.

One end of each side strap 16A and 16B is secured to the baby pouch 12. The other end of each side strap 16A and 16B is adjustably and detachably connectable to the other of the side straps 16A and 16B. The side straps are configured to couple together, for example through a fastener. The fastener may comprise a first connector 20A on side strap 16A and a second connector 20B on side strap 16B. Side straps 16A and 16B are preferably configured to have an adjustable length. The length may be adjustable by sliding the first or second connector along the length of the side strap, so the side straps may be secured snugly around the wearer, for example the wearer's chest. Side straps 16A and 16B may be padded.

Preferably separate from side straps 16A and 16B are shoulder straps 18A and 18B. The shoulder straps are preferably designed to fit any body shape and may be padded at or near an end of the shoulder straps that is secured to the baby pouch, so that the portion 40 of the shoulder strap that extends over the user's shoulders is padded. The shoulder straps 18A and 18B may be detachably connectable to the other of the shoulder straps 18A and 18B, for example by tying. The shoulder straps may alternatively be coupled together through a fastener. Each shoulder strap 18A and 18B is long enough to wrap fully around the user and be comfortably connected to the other shoulder strap. In an example method of tying the shoulder straps in a back-carry position, shown in FIG. 3, each shoulder strap extends over a shoulder of the user and crosses the body, so the shoulder straps 18A and 18B cross each other near the center of the body forming an X shape. Each shoulder strap then extends behind the user and is tied to the other shoulder strap below 55 where the child is seated. For comfort the shoulder straps are preferably wrapped and tied so they lay as flat as possible across the body. The shoulder straps may be wider than the side straps to spread out the load. The shoulder straps may be tied in a similar crossing fashion for a front or side carry. 60 The side straps 16A and 16B may be coupled together before or after the shoulder straps 18A and 18B are wrapped and connected. The side straps may lay over or under the shoulder straps in use. Example carry/in use configurations are shown in FIGS. 4 and 5. The waistband straps are shown 65 coupled together. FIG. 4 shows the carrier as it could be worn in use with the side straps 16A and 16B being coupled together underneath the shoulder straps 18A and 18B. FIG.

5 shows the carrier as it could be worn in use with the side straps **16A** and **16B** being coupled together over the shoulder straps **18A** and **18B**.

Waistband **14** is worn around the user's waist or hips. The waistband **14** comprises a body portion **22** and straps **24A** and **24B**. The straps **24A** and **24B** extend from opposing sides of the body portion **22** and are adjustably and detachably connectable to the other strap **24A** or **24B**. The straps **24A** and **24B** are configured to couple together, for example through a fastener. The fastener may comprise a first connector **26A** on strap **24A** and a second connector **26B** on strap **24B**. The length of the waistband **14** is adjustable by sliding the first connector **26A** and/or second connector **26B** along the respective strap **24A** or **24B**, so the waistband **14** may be secured snugly around the wearer's hips. The waistband **14** may be padded.

Waistband **14** may include a pocket **28**. The waistband **14** may have an additional detachable pocket pouch connected to the waistband to hold smaller items, for example, diapers, wipes, keys and a phone.

The fastener in this description may be any sort of mechanical fastener, for example a buckle, for example a male and female type buckle. Other mechanical fasteners may be used such as loop buckles, D-ring buckles, hook and loop fasteners, ties, buttons, snaps, etc.

The baby pouch **12** comprises a panel **32**. The panel **32** may be height adjustable, designed to grow with the child, and is large enough to hold the baby, infant or small child in a seated position. The child sits in a seat created by the panel with their legs extending through openings defined by the waistband **14** and the side straps **16A** and **16B**. The size of the seat may be adjustable by a drawstring **36** provided at a lower end of the panel **32**. The drawstring **36** may be elastic and may include stoppers **52A** and **52B** at either end of the drawstring **36** to maintain tension in the drawstring **36**. The panel is preferably configured to create a wide seat width and depth, which helps maintain blood circulation in the child's legs by ensuring they are fully supported. Panel **32** may have a pocket **42** on the outside of the panel to carry small items.

There may be a headrest **44** at an upper portion of the panel **32**. The headrest **44** may be padded but the padding is preferably arranged so the headrest **44** may be folded to adjust the height of the headrest depending on the size of the child. The headrest **44** is shown in an example folded position in FIG. 1, for smaller children, and in an example unfolded position in FIG. 2, for larger children. The headrest **44** may be removably fastened to the shoulder straps **18A** and **18B**. This may be through a button **46** attached to a shoulder strap that passes through a loop **48** on a side edge of the headrest. The button **46** may be slidable on a button

strap **50** on the shoulder strap **18A** or **18B** to allow fine adjustments to the height of the headrest **44**. The shoulder straps preferably extend from the upper portion of the panel on either side of the headrest.

5 The carrier may be used to carry small young children, toddlers or babies. The carrier, and especially the baby pouch, is preferably constructed from a strong, structured fabric to offer durability for older babies. The carrier may also be used to safely carry children and babies with low trunk tone, keeping the child's trunk and pelvis in a neutral position, as well as babies who are unable to sit upright unaided. The side straps are positioned on the baby pouch such that there is no opening wide enough for the baby to fall through, allowing a child with low trunk tone to be carried safely and securely on the user's back, front and side.

10 In the claims, the word "comprising" is used in its inclusive sense and does not exclude other elements being present. The indefinite articles "a" and "an" before a claim feature do not exclude more than one of the feature being present. Each one of the individual features described here 15 may be used in one or more embodiments and is not, by virtue only of being described here, to be construed as essential to all embodiments as defined by the claims.

15 The embodiments of the invention in which an exclusive 20 property or privilege is claimed are defined as follows:

25 1. A baby carrier comprising:
a baby pouch;
a pair of shoulder straps extending from opposite sides of
30 an upper portion of the pouch;
a waistband extending from opposite sides of a lower
portion of the pouch; and
35 weight-bearing side straps extending from respective
sides of the pouch intermediate the shoulder straps and
waistband, the side straps being configured to couple
together, the side straps configured so that there is
minimal to no weight bearing through the shoulder
straps when worn.

40 2. The baby carrier of claim 1 wherein the shoulder straps
are configured to be secured to each other by tying.

3. The baby carrier of claim 1 further comprising an
45 adjustable height headrest.

4. The baby carrier of claim 1 in which the baby pouch
forms an adjustable seat for a child.

5. The baby carrier of claim 4 in which the baby pouch
comprises a drawstring.

45 6. The baby carrier of claim 1 in which the waistband
comprises an adjustable buckle.

7. The baby carrier of claim 1 in which the side straps
comprise an adjustable buckle configured to couple the side
straps together.
